UNITED STATES PATENT OFFICE

2,197,652

ELECTRON TUBE

Willi Stattz, Brieselang, Ostholsteinland, and Friedrich Malsch, Berlin-Charlottenburg, Germany, assignors to General Electric Company, a corporation of New York

Application March 30, 1938, Serial No. 198,942
In Germany April 8, 1937

1 Claim. (Cl. 250—150)

The present invention relates to electron tubes and more particularly to beam tubes which employ secondary emission. The primary object of the invention is to provide a tube of the type referred to and in which an improved control is exercised over the number of secondary electrons produced at the target and the number of secondaries which actually reach the anode. In brief, our invention contemplates an improved 10 electron focusing effect for controlling the production of the secondaries and an improved arrangement of electrodes for controlling the number of secondaries which reach the anode.

The invention will be better understood when 13 considered in the light of the following specification and the accompanying drawing in which Fig. 1 is a diagrammatic view of a tube provided with a variable focusing arrangement, and Fig. 2 shows a tube in which the number of secondaries reaching the anode is controlled by the relative position 20 of the secondary emission element with respect to the anode.

In Fig. 1, numeral 1 designates a highly evacuated envelope which contains a source of primary electrons, preferably an indirectly heated cathode, indicated diagrammatically by the circle 2. Positioned about three sides of the cathode, there is a rectangular shield member 3, open at one side and charged to such a potential as to produce an initial focusing of the electron stream. At the opposite end of the tube there is mounted an electrode structure for receiving the beam. Secondary electrons are generated at various surfaces on this structure when the latter is struck 30 by the primary electrons which move through the tube at high speed. A coil indicated at 5 is mounted outside of the envelope between the said electrode structure and the cathode for the purpose of producing a magnetic field which changes 35 the focus of the beam, depending upon the current passing through the coil. When the beam is constricted to a relatively small size, it strikes a circular plate member or collecting electrode 6 which is provided with a cylindrical flange 7. 40 Any secondary electrons generated at the plate 6 are intercepted by the cylindrical member 7.

At the same end of the tube as the plate member 6, there is provided a frusto-conical metal member 8 which surrounds the member 6 and 50 has a central opening 9 at its apical portion sufficiently large for the electron beam freely to pass through when the beam is constricted to a relatively small size by the magnetic focusing field. The outer surface of the conically shaped 55 member 8 is preferably coated with a material

such as alkaline earth oxide which readily generates secondary electrons when struck by a fast moving beam of primary electrons. The beam is accelerated through the tube by suitably applied potentials. It is apparent that the current through the coil 5 may be so controlled as to constrict the electron beam to a small size such as to form a focal spot entirely within the cylinder 1, in which case substantially all of the generated secondaries are intercepted by the cylinder. This 19 position of the beam is indicated roughly by the dot and dash lines 10. On the other hand, the current through the coil 5 may be such as to cause or permit the electron beam to spread out or distribute itself, as indicated by the dotted lines 11, and to strike for the most part the outer surface of the member 8. The number of secondaries generated at the surface 8 may be greatly in excess of the number of primaries reaching 20 said surface. These secondaries are caused to move by means of a suitably applied accelerating field toward an anode 12 which conveniently may take the form of a cone-shaped member having a large opening. As the current through the coil 5 is varied in accordance with the variations of a control potential derived for example from a source 5a, the focus of the beam is also varied and the number of secondaries produced at the element 8 is correspondingly changed. There is a 25 similar change in the number of secondaries 30 reaching the anode, thus giving rise to variations in the anode current. These current variations therefore represent in amplified form the changes of current passing through the coil 5 and can be used in any suitable and well-known manner. 35 Instead of providing the cylinder 1 for intercepting secondary electrons incidentally generated at the plate 6 and instead of providing the conically shaped anode 8, we may employ the member 6 as the main secondary emission element for controlling the anode current. In this case the plate 6 40 may be provided with two or more annular surfaces of different secondary emission properties obtained in any well-known and suitable manner so that as the focus of the electron beam is 45 changed by the magnetic field, secondary electrons are generated at the surface of the plate 6 in a variable manner, depending upon which of the annular surfaces is struck by the electron beam. It is apparent that the current through 50 the coil may be such as to change the distance of the focal point of the beam with respect to the cathode so that the focal point may be positioned either in front of the plate 6 or beyond the plate 6, in which case the size of the focal spot 55

is also changed and the secondary emission from the various annular surfaces controlled in like manner. The secondary electrons obtained in this manner may be caused by the application of suitable potentials to flow directly to the anode 12 and cause a change in the anode current.

Instead of providing a magnetic field for controlling the size of the electron beam, we may utilize an electrostatic form of control for this purpose. For example, a metal cylinder may be mounted within the envelope charged to a variable potential, or any other suitable form of electrostatic focusing means may be employed.

Instead of employing an electric focusing arrangement for controlling the number of secondary electrons which reach the anode, we may use a beam deflection structure for this purpose. Thus in Fig. 2, the anode 13, which may comprise a flat sheet of metal, is positioned in adjacent parallel relation with respect to one of the plates 14 of a multi-sectioned secondary emitter element. The plates 14 which preferably are mounted normal to one another, as shown in the drawing, may be coated on the side facing the cathode with any well-known and suitable material which profusely emits secondary electrons. The cathode 15 may be of the indirectly heated type as in the case of the corresponding element shown in Fig. 1. There is a pair of plates 16 mounted respectively on each side of the cathode. These plates may be negatively biased with respect to the cathode in order to constrict the size of the electron beam. Further control of the size of the electron beam may be exercised through a cylinder 17 which surrounds the deflecting plates 16 of the cathode and which may be charged to any suitable positive potential. It will be noted that this cylinder extends considerably beyond the deflecting plates 16 in order effectively to exercise the necessary focusing control.

The negative potential on one or both of the plates 16 may be controlled in any well-known and suitable manner, thus making one of the plates more negative with respect to the cathode than the other plate. Under these conditions, the electron beam which is roughly indicated by the dotted lines 18 will swing across the tube

and change its point of impact with the secondary emission elements 14. It is apparent that due to the dissymmetry of the position of the anode 13 with respect to the elements 14, the anode will receive more secondary electrons when the electron beam strikes the lower of the two plates 14. Obviously, other structures can be devised in which the lack of positional symmetry between the anode and the secondary emission element may be obtained. The changes in the anode current brought about by the deflection of the electron beam 18 may be utilized in any suitable and well-known external circuit. These current changes will correspond in a general way to the changes in the bias potentials applied to the deflecting elements 16.

What we claim as new and desire to secure by Letters Patent of the United States, is:

An electric discharge device comprising an electron source for producing a beam of primary electrons, a frusto-conical target having its apical portion directed toward the cathode and having a central opening in such portion, the said target being conditioned to emit secondary electrons upon the impingement of primary electrons thereon, a collecting electrode positioned behind the said target for receiving primary electrons which pass through the said central opening in the target, focus-controlling means positioned between the electron source and the said target and effective when energized by a variable control potential to produce corresponding variations in the cross-section of the beam of primary electrons without changing the position of its central axis, means for applying a variable control potential to said focus-controlling means, thereby to vary the relative proportions of the primary electron beam which respectively impinge on the said target and pass through its said central opening, and an anode positioned adjacent to the target for receiving a variable number of secondary electrons emitted by the target in accordance with variations in the proportion of the primary beam current impinging thereon.
